UNITED STATES PATENT OFFICE.

WILLIAM HENRY JENKS, OF WINCHESTER, MASSACHUSETTS, ASSIGNOR TO L. C. CHASE & COMPANY, OF BOSTON, MASSACHUSETTS, A COPARTNERSHIP.

FOOTWEAR AND ARTIFICIAL-LEATHER UPPER MATERIAL THEREFOR.

Application filed September 20, 1928. Serial No. 307,125.

- This invention has to do with a construction of footwear such as shoes and particularly such as slippers and with an artificial leather material for the uppers thereof.
- 5 The object of the invention is to provide an artificial leather material of novel, practical and useful qualities and characteristics for footwear uppers which will enable the footwear such as shoes and slippers to be constructed at low cost by the processes heretofore employed in the manufacture of leather footwear and of pleasing appearance and high wearing qualities.
- 10 The nature and object of the invention will appear more fully from the accompanying description and drawings and will be particularly pointed out in the claims.
- 15 In the drawings:
- Fig. 1 is a perspective view of an ordinary form of slipper.
- 20 Fig. 2 is a diagrammatic view to illustrate the composition of the upper material.
- A preferred form of material embodying the invention is particularly designed for use 25 in the construction of uppers of light weight footwear such as slippers. Such a material is made up of four layers. First, a fine cotton fabric such as a sheeting of fine count. Second, a moleskin fabric presenting the 30 usual teazled face. Such a fabric in its teazled face presents a desirable lining or inner surface for a slipper and renders unnecessary a separate lining material such as commonly employed in slipper manufacture.
- 35 This moleskin fabric gives the qualities of warmth and comfort heretofore attained, for example, by the use of a felt lining. Third, a relatively heavy body of cementitious rubber compound between the two above-mentioned layers, interpenetrating and uniting these layers. This third layer not only serves to unite the two fabric layers into an integral sheet of material, but it gives a plasticity to the material which enables it in the operations of manufacturing the slipper or other 45 piece of footwear to be molded snugly to the last and to be brought into conformity therewith without wrinkling. Any of the suitable cementitious rubber compounds heretofore employed in the manufacture of so-called double texture fabrics may be employed for this purpose, but the layer should be relatively heavy so as to give body and plasticity to the sheet of material. Fourth, a relatively 50 light pyroxylin coating on the fine cotton fabric. This coating forms the exterior surface of the sheet material and the exterior surface of the upper of the footwear. By using a fine cotton fabric and a relatively thin layer of pyroxylin coating, the required flexibility of the sheet material is obtained without danger of the pyroxylin coating cracking. This pyroxylin coating may be of the usual compositions employed in making artificial leather materials and may present any desired color and be embossed to present any desired grain effect so that the exterior surface of the sheet material is capable of being finished equally with leather to present the various color and grain effects producible 55 with leather.
- The sheet material made in accordance with this invention presents an integral lining material and is characterized by the following qualities. First, it is readily moldable to 60 the last in the course of the manufacture of the slipper or other footwear. Second, it is stitchable upon the usual stitching machines employed without splitting. There is no tendency for the material to split or separate 65 between the successive needle penetrations and the stitches may be pulled tight to the extent required without injuring or weakening the material for the purpose of incorporation into the footwear. Third, it is finishable upon its exterior surface to present any 70 desired colored and grain effect equally with leather.
- The sheet material made in accordance with this invention presents an integral lining material and is characterized by the following qualities. First, it is readily moldable to 75 the last in the course of the manufacture of the slipper or other footwear. Second, it is stitchable upon the usual stitching machines employed without splitting. There is no tendency for the material to split or separate 80 between the successive needle penetrations and the stitches may be pulled tight to the extent required without injuring or weakening the material for the purpose of incorporation into the footwear. Third, it is finishable upon its exterior surface to present any 85 desired colored and grain effect equally with leather.
- A further valuable characteristic of this material as above described lies in the fact 90 that it eliminates the necessity of a separate lining material, its inner surface presenting the required lining surface. The teazled surface of the moleskin has the required 95 "feel" for a slipper lining. Furthermore, this moleskin layer before being incorporated into the material may be dyed to give any desired color to the inner or lining surface of the slipper.
- The material of this invention may also be 100 made, within the scope of the invention in its broader aspects, without the use of a moleskin fabric and by the use instead of any fabric suitable to give the required strength and plasticity, such, for example, as a cotton drill. Such a material possesses all the other 105 qualifications and characteristics hereinbefore set forth except that of presenting a

lining surface and presents a desirable upper material for other forms of footwear such as shoes.

It is to be understood that the term "upper" as used herein includes that part of the slipper or other footwear above the sole. I believe I am the first to devise and use a two-ply fabric material of the character herein disclosed for such uppers.

Having thus described the invention, what is claimed as new, and desired to be secured by Letters Patent, is:

1. An integral upper and lining sheet material for slippers characterized by the qualities, viz: of being moldable to fit a last, stitchable without splitting and finishable on its exterior surface in any desired color and grain equally with leather and composed of four layers, viz: a fine cotton fabric, a mole-skin fabric with its teazled face exposed to form the inner surface, a relatively heavy body of cementitious rubber compound between, interpenetrating and uniting the two fabrics, and a relatively light pyroxylin coating on the fine cotton fabric presenting the desired color and finish and exposed to form the exterior surface.

desired color and finish and exposed to form the exterior surface

2. A slipper having an integral upper and lining composed of the sheet material defined in claim 1.

3. An integral upper material for footwear characterized by the qualities, viz: of being moldable to fit a last, stitchable without splitting and finishable on its exterior surface in any desired color and grain equally with leather and composed of four layers, viz: a fine cotton fabric, a backing fabric, a relatively heavy body of cementitious rubber compound between, interpenetrating and uniting the two fabrics, and a relatively light pyroxylin coating on the fine cotton fabric presenting the desired color and finish and exposed to form the exterior surface.

4. A piece of footwear having an upper composed of the sheet material defined in claim 3.

In testimony whereof, I have signed my name to this specification.

WILLIAM HENRY JENKS.
